Hugo M. Ditto, Newton, Mass., assignor to Marine Optical Manufacturing Co., Roslindale, Mass., a corporation of Massachusetts

Application September 29, 1958, Serial No. 52,788

Term of patent 14 years

(Cl. D57—1)

Fig. 1 is a front perspective view of a spectacle frame or the like, showing my new design;

Fig. 2 is a front elevational view thereof; and

Fig. 3 is a side elevational view thereof taken from the left side of Fig. 1.

The dominant features of my new design reside in the portions shown in full lines.

I claim:

The ornamental design for a spectacle frame or the like, substantially as shown and described.
